UNITED STATES PATENT OFFICE.

CALVIN E. GARDNER, OF BAKERSVILLE, PENNSYLVANIA.

DESIGN FOR A WALL-DESK.

SPECIFICATION forming part of Design No. 32,596, dated April 24, 1900.

Application filed June 14, 1897. Serial No. 640,780. Term of patent 14 years.

To all whom it may concern:

Be it known that I, CALVIN E. GARDNER, a citizen of the United States, residing at Bakersville, in the county of Somerset and State of Pennsylvania, have invented and produced 5 a new and original Design for a Wall-Desk, of which the following is a specification, reference being had to the accompanying drawing, forming a part of this specification.

In the drawing I have shown a perspective view of my design, and by reference thereto it will be seen that the leading features consist of the horizontal shelf 1, having a back 2. Projecting from the rear edge thereof and 5 at right angles thereto also an inclined leaf 5, which slants downwardly from the front edge of the shelf to which it is connected. At the rear edge of the shelf are a number of forwardly-extending vertical flanges arranged

in pairs, one pair being located at each end of the shelf. Supported by each pair is a panel 4, which is flush with the flanges at their ends, but which overlaps them at their sides. The back 2 is ornamented at its upper edge by a vertical disk 3, in the center of which is mounted 25 a mirror 3', and at either side of the disk 3 is a shell-like ornament 2', inclining toward the disk.

Having thus described my invention, what I claim is—

The design for a wall-desk as herein shown and described.

In testimony whereof I affix my signature in presence of two witnesses.

CALVIN E. GARDNER.
